UNITED STATES PATENT OFFICE.

EDWARD F. KING, OF WAKEFIELD, RHODE ISLAND.

DESIGN FOR A TIRE SHOE-HORN.

59,848.

Specification for Design.

Patented Nov. 29, 1921.

Application filed August 15, 1921. Serial No. 492,520. Term of patent 3½ years.

To all whom it may concern:

Be it known that I, EDWARD F. KING, a citizen of the United States, residing at Wakefield, in the county of Washington and State of Rhode Island, have invented a certain new, original, and ornamental Design for a Tire Shoe-Horn, of which the following is a specification.

In the accompanying drawings which form a part of this specification—

Figures 1, 2, and 3, are a side, face, and rear view respectively of a tire shoe horn embodying my design.

I claim:

The ornamental design for a tire shoe horn, as shown.

EDWARD F. KING.
